SUCTION ROLL

William Hulse Millspaugh, Catawba Island, Ohio

Application January 5, 1939, Serial No. 249,399
In Great Britain January 7, 1938

6 Claims. (CL 92—53)

This invention relates to suction rolls for use for paper and pulp making and also for use in other industries such as the textile industry, and its primary purpose is to remove water in paper making from the upper side of a felt where paper is pressed between two felts, as for example in making heavy papers on a cylinder machine.

When wet webs of paper are carried by felts through presses the water always goes to, into and through the felt. With old type imperforate presses the water, notwithstanding an accumulation at the nip on the lower roll of a press, or a part of the water at least, does not run off. This accumulation of water limits the speed and is a source of trouble, causing crush. The suction press roll overcame these difficulties at the lower roll. With two felts the accumulation of water at the nip of the plain top roll caused endless trouble and many devices have been used to remove such water, for instance plain slice boards to confine the water to a narrow area near the roll and cause it to run off the two edges of the felt into a pit under the machine. Numerous suction slices have been made and used, one example being shown in my U. S. Letters Patent No. 957,981. However, even with suction slices such as shown in the said prior patent the water must accumulate until it reaches and can be caught by the suction slide. Inverted box suction press rolls of existing designs have been tried but due to structural limitations and nature's laws, the water could not be evacuated and a pond was held in the box and perforations of the sheet to be re-absorbed and also carried through the nip to be thrown out by a centrifugal force or gravity according to speed.

The present invention has for its object effectually to remove the water at the nip by receiving and evacuating the water as expressed and to permit of greater pressures being applied to the top roll, and as the nip is freed from water and crush, flowering and the like is stopped.

For this purpose according to the invention, a suction press or top couch roll is provided internally with a suction box having a small capacity receiving chamber between parallel longitudinal sealing walls or packings contacting with the inner wall of the shell, the ends of the chamber being sealed by heads which also contact with the shell, the suction box being also provided with a raised portion or rib or equivalent arranged longitudinally of the interior of the suction box and provided with passages connecting the chamber and interior of the suction box through which water and air can be drawn. The

passages may be provided with externally threaded tubes each preferably having a head for adjustment by a spanner. The suction box may be provided with a removable cover to provide access to the interior of the box for adjustments and for introducing additional passages or closing some of them if desired. A suction roll shell with suction box according to the invention may be used as an upper roll in conjunction with a lower suction roll or non-suction roll or cylinder mould.

In the accompanying illustrative drawings, Fig. 1 is a sectional end elevation of a suction roll shell and its suction box made according to and embodying the present invention. Fig. 2 is a longitudinal section through part of the suction roll shell and suction box shown in Fig. 1. Fig. 3 is another longitudinal section showing upper and lower rolls and bearings therefor and adjusting means for the box, both suction rolls being rubber covered. Fig. 4 is a sectional end view, more or less diagrammatic, showing a suction roll shell and suction box embodying the invention, associated with a lower forming mould of a paper making machine. Fig. 5 is a cross section, more or less diagrammatic, showing a suction roll shell and suction box embodying the invention, associated with a lower suction roll, with two felts and web of paper between them. Fig. 6 is a view similar to Fig. 1 showing a modified construction and Fig. 7 is a section on the line VII—VII of Fig. 6.

Referring to the drawings, a suction press or top couch roll according to the invention comprises a bronze roll 1 perforated in the usual manner for suction presses, and it may, as shown, preferably have a rubber covering 2 in which the holes 2a therein are aligned with the holes 1a in the bronze shell. Arranged within the shell 1 is a suction box 3 between which and the inner wall of the shell is a narrow longitudinal chamber 4 recessed in or formed between a packing strip or strips 5 which may be of Babbitt metal or fibre chemically treated, or rubber with textiles, or wood, or any other suitable material. The suction box 3 is provided with an internal upstanding rib 6 extending nearly the perforated length of the shell, the rib being provided with a number of passages 7 communicating with the interior of the box and the chamber 4 and within which are arranged tubes 8 each provided at its inner end with a head 8a for a spanner or with the equivalent such as a passage or slot. The rib 6 is of such a height that water drawn into the interior of the suction box 3 will be prevented from gathering above the passages 7, or the ends

of the tubes 8 inserted in the passages. The suction box is provided with a removable cover 9 whereby access can readily be gained to the interior of the box to introduce additional passages or tubes or to close some of them if desired. The suction box is constructed to give the water accumulated therein free travel to its extreme end and to a pump for complete drainage of the water from the box.

The passages or tubes 8 forming communication between the chamber 4 and the interior of the suction box 3 are of such a number and size that they have but slightly greater carrying capacity for air and water than the amount entering the chamber to the end and purpose of draining the water from the upper side of the upper felt without allowing an accumulation within the chamber between the sealing strips, where a pool of water held in the chamber would be re-absorbed by the felt and paper and carried through the nip, unless sucked away as described.

A roll 1 constructed as described may be arranged over a lower smooth imperforate roll to form a suction press assembly with a felt carrying on its under surface a web of paper adapted to pass between the rolls with the felt in contact with the upper suction roll.

Or, as shown in Fig. 4, a roll 1 may be used as a couch roll mounted over a paper web-forming mould cylinder 10 of a paper making machine provided with a felt 11 travelling over the cylinder, the upper roll contacting with the felt to exert a regulatable pressure on the felt having a web of paper on the under surface thereof, whereby water is extracted therefrom and the paper web caused to leave the web forming surface and to adhere firmly to the underside of the said felt which may travel onward to similar units, the paper web from each adhering to the preceding web.

A roll 1 constructed as described and as shown in Fig. 5, may also be employed as the top roll in combination with a lower suction roll 12 provided with a rubber covering 13 according to the specification of my British Letters Patent No. 457,858. The rolls 1 and 12 would be offset so that felts 14 and 15 with paper 16 between have sufficient lap about the upper roll 1 so that all shell perforations opening into the chamber 4 should be covered by the upper felt 14, that is, to the outside of the packings, so that holes communicating with the suction box do not have access to the atmosphere which would reduce the vacuum necessary within the chamber and interior of the suction box to lift the water.

The arc over the suction box 17 of the lower roll 12 at the approach side is not fully covered by the felts so that a large volume of air at low pressure can be drawn into the said lower suction box through the shell perforations with the water flowing from the bite of the two rolls onto the arc of the lower roll which is in communication with the lower suction box, in such manner that gravity, assisted by the induced air pressure, quickly removes the water from the lower perforated roll surface, as described in the specification of my said British Letters Patent No. 457,858. In that invention the felts should run practically vertical or steeply inclined and to install rolls according to the said earlier specification in existing machines sometimes involves considerable changes, whereas according to the present invention the rolls may be installed in place of the ordinary presses, where felts run nearly

horizontally, with little interference to production.

Or the lower roll 12 may be a smooth imperforate roll, the two felts with web of paper between them being passed between the two rolls in such manner that an arc of the upper roll equal to the overall width of its suction box chamber is covered by the felts, the interior of the chamber of the upper roll being positioned on the approach side of the bite.

The theory of this invention, namely, restricted passages through which water and air pass at high velocity, being understood, various modified constructions may be employed without departing from the invention to secure this restricted communication between the chamber and interior of the suction box, for instance as shown in Figs. 6 and 7, in which the lower chamber comprises two compartments 4^a, 4^b separated by packing 5^a containing slots 5^b. Some of such constructions may be provided with regulating means to define the net opening of the passages.

Top and bottom rolls are described. It is to be understood however that the rolls may be arranged in any relation wherein the suction box of this invention lies below the contacting line with its co-acting roll, should the rolls coat with their axes on a horizontal plane. A suction roll as described may be used without a coacting roll, where water is to be lifted, for example, as a suction roll used to transfer a web of paper from a wire or felt.

What I claim is:

1. A hollow cylindrical suction press roll, a stationary suction box within the roll and near the lower part of said roll having parallel longitudinal sealing walls and sealing heads at the ends of the walls, said walls and heads contacting with the lower part of the inner surface of the roll and forming a small capacity receiving chamber, an upstanding longitudinal rib above said chamber with its top above an adjacent portion of the suction box, said rib being provided with longitudinally spaced restricted passages from the chamber through which water and air can be raised through the top of said rib into the suction box.

2. A suction roll press assembly wherein a suction roll according to claim 1 is mounted over a lower suction press roll between which two felts with a web of paper between them may be passed in contact with an arc of the upper press roll corresponding to the overall width of its suction box chamber, the chamber of said upper roll being positioned on the approach side of a plane through the bite and wherein the arc over the suction box of the lower roll at the approach side of a plane through the bite is not fully covered by the felts.

3. A suction press roll provided internally with a stationary suction box within the roll and near the lower part of said roll having along its lower edge a small capacity receiving chamber between parallel longitudinal sealing walls or packings contacting with the lower part of the inner wall of the shell, the ends of the chamber being sealed by heads which also contact with the shell, the box being also provided with a raised portion or portions arranged longitudinally of the interior of the suction box above said chamber and provided with adjustable passages from the top of the raised portion or portions to the chamber through which water and air can be raised, and a removable cover for the suction box whereby access to said passages may be had.

4. A suction press roll according to claim 1,

wherein the passages connecting the chamber and interior of the suction box are restricted by the insertion of tubes therein.

5. A suction press assembly wherein a suction roll according to claim 1 is mounted over a lower suction press roll between which two felts with a web of paper between them may be passed in contact with an arc of the upper press roll corresponding to the overall width of its suction box chamber, the chamber of the upper roll being 10 positioned on the approach side of a plane through the bite.

6. A suction press assembly wherein a suction roll according to claim 1, is mounted over a lower smooth imperforate lower roll between which a felt arranged to carry a web of paper may be passed in contact with an arc of the upper roll corresponding to the overall width of its suction box chamber, the interior of the chamber of the upper roll being positioned on the approach side of a plane through the bite.

WILLIAM HULSE MILLSPAUGH.
